Primary Examiner — Ryan Harvey(57) **CLAIM**

The ornamental design for a squat wrap, as shown and described.

DESCRIPTION

FIG. 1 is a perspective view of a squat wrap showing my new design;

FIG. 2 is a top view thereof;

FIG. 3 is a bottom view thereof;

FIG. 4 is a front view thereof;

FIG. 5 is a rear view thereof;

FIG. 6 is a top view of a squat wrap turned to the left and vertically rolled showing a rod in broken lines of which the rod is not part of the design sought to be patented; and, FIG. 7 is a top view of a squat wrap horizontally rolled showing a rod in broken lines of which the rod is not part of the design sought to be patented.

In the drawings, the broken line showing of dash-dot-dash stitch lines represent unclaimed portions of the claimed design and form no part thereof. Similarly, the evenly-spaced broken lines comprising the words "THE SQUAT WRAP" and depicting the male and female logo figures represent unclaimed portions of the claimed design and form no part thereof.
